UNITED STATES PATENT OFFICE.

HERRMAN S. SARONI, OF MARIETTA, OHIO.

MUSICAL INSTRUMENT.

SPECIFICATION forming part of Letters Patent No. 468,265, dated February 2, 1892.

Application filed January 26, 1891. Serial No. 379,348. (No model.)

To all whom it may concern:

Be it known that I, HERRMAN S. SARONI, a citizen of the United States, residing at Marietta, in the county of Washington and State 5 of Ohio, have invented a new and useful Musical Instrument, of which the following is a specification.

My invention relates to improvements in zithers, which are ordinarily played by direct 10 contact of the fingers with the strings, the thumb of the right hand being armed with a metal hook, and which lack a complete chromatic scale, thus limiting the harmonies otherwise possible.

15 The object of my invention is to furnish an unbroken chromatic scale of tones and by means of keys to enable any pianist to play it at once without special instruction. I attain these objects by the mechanism illustrated in 20 the accompanying drawings, in which—

Figure 1 is a vertical section front view. Figs. 2 and 3 represent different positions of the mechanism; and Fig. 4 is a vertical section of a modified apparatus, similar letters 25 referring to similar parts.

A represents a key similar to those of an organ or piano, with suitable arrangement for dampers. (Not shown in the drawings.)

B is a bracket with openings b b', acting as 30 guides.

C is a square rod with pin c, surrounded by coiled spring c'.

D, Figs. 1, 2, and 3, is a strip of spring-brass or other suitable material attached to 35 the rod C and so shaped that it forms the cam d, the curve d' terminating in a point d'', the whole being technically called "finger." D, Fig. 4, represents a similar apparatus made of wood or similar material, differing from 40 Figs. 1, 2, and 3 in that it is hinged at d''' to the rod C and having the spring d''''.

E is a strip of wood either separate or a continuation of the bracket-wall B, upon which, at e, is pivoted the device F, representing a combination of lever and pawl, (technically "trigger,") terminating in the points f, f', and f''.

G represents a string, of metal, silk, or cat-gut, stretched between two bridges of a sounding-board (not here shown) and running parallel to the key A.

The action of the mechanism is as follows: Pressing upon the key A the finger D, owing

to its cam d and the trigger F, is forced against and past the string G, allowing the latter to 55 vibrate and clearing it in its return upward as soon as the pressure upon A is released and the spring c' is allowed to exert its power. Fig. 1 shows the initial position of both finger D and trigger F. Fig. 2 shows the finger 60 D in contact with the spring G and the position assumed by the trigger F. Fig. 3 shows the position of trigger and finger after contact. The office of the trigger is twofold, the point f' determining the moment when the 65 cam d shall trip from f, and the point f'', pressing against the curve d', causing the trigger to return to its initial position.

When the finger is made of wood and hinged to the rod C, the form of finger and trigger 70 must necessarily be modified, as the former will need a spring of some kind d'''' to force it back to its original position after having been dislodged by the trigger. (See Fig. 4.)

It is obvious that other modifications of 75 form and material may be made without departing from the spirit of my invention. The finger may be attached directly to the key. It may be made of a combination of wood and metal. The trigger may be actuated by springs and thus become a simple lever; but whatever the form of the one or the other, they must be formed so that the finger after snapping the string must recede, so as not to impede the vibration, and the trigger 85 or lever must allow the return of the finger to its initial position.

Having now fully described my invention, what I desire to claim and secure is—

1. In a mechanism for picking zithers, the 90 trigger F, provided with points f f' f'', constructed and arranged to operate substantially as set forth.

2. The combination of the trigger F and finger D with the rod C, the springs c' d''''', and 95 the key A, for the purpose herein specified.

3. The combination of the key A, or a series of such keys, the rod C, the finger D, and the trigger F with a series of strings stretched over the sounding-board of a shallow or zither 100 body, for the purpose herein set forth.

HERRMAN S. SARONI.
